Primary Examiner — Karen S Acker*Assistant Examiner* — Wendy Arminio(74) *Attorney, Agent, or Firm* — Dorsey & Whitney LLP**CLAIM**

I claim the ornamental design for a covering for an architectural opening, as shown and described.

DESCRIPTION

FIG. 1 is a top-left isometric view of a covering for an architectural opening.

FIG. 2 is a front elevation view of the covering of FIG. 1.

FIG. 3 is a left side elevation view of the covering of FIG. 1.

FIG. 4 is a right side elevation view of the covering of FIG. 1.

FIG. 5 is a top plan view of the covering of FIG. 1.

FIG. 6 is a bottom plan view of the covering of FIG. 1; and, FIG. 7 is a rear elevation view of the covering of FIG. 1.

The broken lines depict features of the covering for an architectural opening that form no part of the claimed design. The covering for an architectural opening is shown with symbolic breaks in its length and width. The appearance of any portion of the article between the break lines forms no part of the claimed design.
